The design for the water ease, as shown and described.

DESCRIPTION

FIG. 1 is a perspective view of the invention;
FIG. 2 is a top view of the invention;
FIG. 3 is a bottom view of the invention;
FIG. 4 is a right side view (left side mirror image) of the
invention;
FIG. 5 is a front view of the invention; and,
FIG. 6 is a rear view of the invention.

1 Claim, 2 Drawing Sheets*FIG. 1*

FIG. 2

FIG. 3

FIG. 4

FIG. 5
